CLAIM

The ornamental design for a case for tablet computer, as shown and described.

DESCRIPTION

FIG. 1 is a front perspective view of a case for tablet computer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view thereof in an open position;

FIG. 10 is a front perspective view thereof in its folded configuration; and,

FIG. 11 is a front perspective view thereof in its folded configuration with a stylus pen therein.

The broken lines throughout the drawing figures depict portions of the case that form no part of the claimed design. The broken lines and regions bounded by broken lines form no part of the claimed design.

1 Claim, 11 Drawing Sheets
